ATTORNEY.

UNITED STATES PATENT OFFICE

JENNIE B. HAMILTON, OF WESTFIELD, MASSACHUSETTS

SIGN

Application filed July 5, 1932. Serial No. 620,787.

This invention relates to improvements in signs or markers, and is directed more particularly to signs or markers adapted to embrace a support and having removable or interchangeable characters associated therewith.

The principal objects of this invention are directed to the provision of a sign which is adapted for removably attaching to the edge of a shelf or ledge and has removable characters or figures on its forward face. According to one feature of the invention the sign is constructed and arranged so that it may embrace a support such as a shelf or ledge, and it may be made of metal, with a forward display face provided with means for detachably receiving characters. According to another feature of the invention an ornamental face is provided for the forward side of the sign which may be of an ornamental nature to provide various finishes and color effects so as to contrast or scheme with the detachable characters superposed thereon.

Various novel features and advantages of the invention will be hereinafter more fully referred to in connection with the accompanying description of the preferred form of the invention, reference being had to the accompanying drawing in which;

Fig. 1 is a front elevational view of a sign embodying the novel features of the invention.

Fig. 2 is a side elevational view of the same.

Fig. 3 is a perspective view of the sign shown in Fig. 1 looking at the rear side thereof to show certain features of the invention.

Fig. 4 is a view similar to Fig. 1 showing a modified form of the invention, and

Fig. 5 is a view similar to Figs. 1 and 4 showing another modified form of the invention.

The sign as shown in Figs. 1, 2 and 3, has a forward plate 2 which may be called a display plate from the rear side of which extends an upper flange 4 and a lower flange 6. The lower flange is preferably bent to

form a loop 8 and has a relatively flat extremity 10 at the upper side thereof.

The sign will preferably be made from relatively thin resilient material such as metal and when so made with the loop shown, the lower flange is springlike so that it will flex relative to the upper flange 4 and to plate 2 while of course the upper flange is somewhat resilient. The flanges are arranged so as to receive therebetween a ledge or shelf represented by L and since the flanges are resilient the shelf or ledge will be yieldingly gripped therebetween. In that way the sign is supported so that its forward plate portion may extend in a more or less vertical position.

The sign may be in any length desired so that it may extend across a shelf or ledge and there may be as many of the upper and lower flanges therealong as may be desired for embracing the shelf. The sign being described is relatively short and has flanges which are equal in length to the length of the sign. It will be understood that a longer sign may of course have flanges extending the entire length thereof. The flange 6 is preferably provided with slots 12 in spaced relation so that a gripping plate 14 may be struck up from the material of the flange and lie more or less in parallelism with the upper flange 4 and in alignment with portion 10.

This plate 14 is arranged to abut the lower side of a shelf or ledge. The flange 6 is yieldable or resilient and the plate 14 is also yieldable in itself for bearing against the shelf to prevent the sign from being displaced. To more securely engage the shelf the plate 14 may have one or more prongs such as 16 on its opposite corners the ends of which will impinge the shelf.

Where the sign is made of considerable length there may be a plurality of flanges and plates similar to that described associated with the sign. Where a sign of considerable length is used continuous flanges may be employed having a plurality of similar plates 14 struck up in spaced relation along said flange.

Pockets 20 arranged in series or pairs are

provided on the outer front face of the plate 2. These are struck up from the body of the plate and have slits or slots 22 associated therewith so as to have open sides or mouths 5 preferably arranged so the open side of one pocket is directed towards an open side of an opposite pocket.

The face of the plate 2 may be of one color and characters such as 24 are superposed thereon which have tabs or lugs 26 receivable in the pockets. In this way the characters are readily attached to and removed from the plate and are held against shifting thereon.

15 As will be seen the characters are readily and easily inserted in the pockets and removed therefrom to facilitate the interchangeability thereof. Where a relatively long sign is used the pockets may be spaced 20 at desired intervals therealong to receive and accommodate various characters such as letters and the like.

In the form of the invention shown in Fig. 4, a sign S' comprises a front plate 30 and rearwardly extending flanges such as 32 have been described in connection with Figs. 1, 2 and 3. In this form of the invention an auxiliary plate or decorative member such as 32 is associated with a front plate 30. 25 Where the sign is made from metal which may be difficult to color, this plate 32 may be made of relatively thin celluloid or the like, of a certain color and it is secured to the plate in some suitable manner as by 30 means of rivets 34.

By securing an auxiliary member such as 32 to the plate 30, it is possible to take advantage of the finish and the color of such material as celluloid and the like, and in 40 that way overcome difficulties experienced with the coloring of the plate 30.

In this form of the invention the member 32 is provided with a plurality of pockets 36 which as in the previous case are formed by 45 slotting the material and pressing the body thereof outwardly so as to form pockets to have open sides directed towards one another.

Characters 24 as is in the former case have 50 lugs 26 which are receivable in the pockets 36 in the manner explained. In this form of the invention the characters may be of one color and varied in relation to the color of the plate 32.

55 In the form of the invention shown in Fig. 5 the sign S'' has a forward plate 40 and upper and lower flanges such as have been described which extend rearwardly therefrom. The plate 40 is provided with

60 pockets 46 which may be formed by slitting the plate 40 and pressing portions thereof above outwardly beyond the plane of the face of the plate, after the manner described in connection with Fig. 1.

65 A face plate 42 in this form of the inven-

tion may be of ornamental material such as celluloid, or even colored metal, and has suitable cut-outs to receive the pockets 46 and is provided with tongues or lugs 48 for insertion in the said pockets. In this way the plate 42 is removable from the plate of the sign and is held therein by the tongues which are received in the pockets. 70

Characters such as 24 have upper and lower lugs 26 which are also receivable in the pockets 46 and with the characters superposed on the plate 42 both the plate 42 and the characters are held against the plate by the pockets and yet are readily removable therefrom for any changes which 80 may be desired. 75

The pockets may take any form desired and in all cases will preferably be struck up from the body of the plate member which carries them and will have open ends 85 or slots for receiving lugs or tabs of the characters to be associated with the sign.

Having described the invention in the form at present preferred, what I now desire to claim and secure by Letters Patent 90 of the United States is:

1. A sign of the class described comprising in combination, a plate having flanges extending rearwardly therefrom at upper and lower sides, one of said flanges being formed with a loop adjacent its jointure with the plate whereby said flange is yieldable, said flange being provided with slots to form a part struck up from said flange to bear yieldingly against a support between said flanges and a projection on said part to impinge said support. 100

2. A sign of the class described comprising in combination, a plate, an upper flange extending rearwardly from the upper side thereof, and a lower flange extending from the lower side thereof disposed in an inclined relation and yieldable relative to said upper flange, one of said flanges being provided with slots to form a part struck up from the main body thereof into substantial parallelism with said other flange. 105

3. A sign of the class described comprising in combination, a plate, an upper flange extending rearwardly from the upper side thereof, and a lower flange extending from the lower side thereof disposed in an inclined relation so as to be yieldable relative to said upper flange, a part of said lower plate being struck up from the main body thereof into substantial parallelism with said upper plate and said part being provided with an upwardly extending projection. 110

4. A sign of the class described comprising in combination, a plate member having relatively yieldable spaced flanges at the rear side thereof for embracing a support, an auxiliary plate member overlying said first-named plate member, pockets associ- 115 120 125 130

ated with one of said plate members and a character having lugs receivable in said pockets.

5. A sign of the class described comprising in combination, a plate member having relatively yieldable spaced flanges at the rear side thereof for embracing a support, an auxiliary plate member overlying said first-named plate member, pockets associated with 10 one of said plate members and a character having lugs receivable in said pockets, the said auxiliary plate being secured to the first-named plate.

6. A sign of the class described comprising in combination, a plate, an auxiliary plate secured thereto having pockets formed 15 on its forward face and characters overlying said auxiliary plate having lugs receivable in said pockets whereby said characters 20 are held in position.

7. A sign of the class described comprising in combination, a plate having pockets on the forward face thereof provided with 25 openings, an auxiliary plate having openings around said pockets and lugs receivable in said pockets and a character overlying said auxiliary plate having lugs in said pockets.

In testimony whereof I affix my signature.
30 JENNIE B. HAMILTON.
